CLAIM

The ornamental design for a head rest, as shown and
described.

DESCRIPTION

FIG. 1 is a perspective view of a head rest, showing my
new design;

FIG. 2 is a top plan view thereof;

FIG. 3 is a bottom plan view thereof;

FIG. 4 is a side elevational view thereof, the opposite
side elevational view being identical;

FIG. 5 is a rear elevational view thereof; and

FIG. 6 is a front elevational view thereof;

FIG. 1

FIG. 2

FIG. 3

FIG. 4

FIG. 5

FIG. 6
